J. M. WESTCOTT

DOOR LOCK

Filed June 30, 1927

Patented Dec. 25, 1928.

1,696,466

UNITED STATES PATENT OFFICE.

JAY M. WESTCOTT, OF SYRACUSE, NEW YORK.

DOOR LOCK.

Application filed June 30, 1927. Serial No. 202,601.

This invention relates to a door lock adapted to be installed more particularly in the doors of closed motor vehicles, but obviously may be used in the doors of houses and other enclosures and involves the use of relatively rotatable co-axial shaft sections passing through a suitable opening in the door and provided with separate handles, one at the inside and the other at the outside of the door by which the shaft sections may be rotated and separate devices actuated by the shaft sections for releasing the bolt from its locking position together with suitable devices surrounding the outer axle section and relatively adjustable angularly to establish different combinations whereby when adjusted to predetermined positions, will permit the unlocking of the bolt by the outer handle but normally prevent the unlocking of the bolt until the proper relative adjustments of the devices are made.

The main object is to provide a simple, compact and efficient lock of this character which may be made and sold at a comparatively low cost and which when installed will permit the bolt to be readily unlocked from the inside of the door by the turning of the inner handle in either direction but will prevent the unlocking of the bolt from the outside handle until the controlling devices are re-adjusted to the predetermined position to release the bolt.

Another object is to permit the controlling devices to be easily and quickly changed to different combinations when desired.

Other objects and uses relating to specific parts of the lock will be brought out in the following description.

In the drawings:—

Figure 1 is a face view of portions of a door and door jamb with my improved lock installed therein.

Figure 2 is an enlarged horizontal sectional view taken in the plane of line 2—2, Figure 1.

Figures 3, 4 and 5 are detail sectional views taken respectively in the planes of lines 3—3, 4—4, and 5—5, Figure 2.

Figure 6 is a detail sectional view, partly in elevation, taken in the plane of line 6—6, Figure 2.

Figure 7 is a detail sectional view taken in the plane of line 7—7, Figure 2.

This lock is adapted to be installed in and upon any door such as an automobile door —A— of a closed car or other enclosure to

cooperate with a suitable keeper in the door frame as —A'— and comprises a main supporting frame —1— adapted to be secured by suitable fastening means as screws —2— to the outer face of the door —A— and across a portion of the edge thereof adjacent the frame —A'—.

The door —A— is provided with a recess or chamber —a— adapted to receive certain portions of the locking mechanism while the frame —A'— is provided with a recess or chamber —a'— for receiving the outer end of the lock bolt and a suitable keeper plate —3—.

The lock proper comprises relatively rotatable co-axial shaft sections —4— and —5— passing through registering openings in the outer plate —1— and inner side of the door —A— respectively so that the inner ends of each shaft section will project into the chamber —a—.

The shaft section —4— preferably extends entirely through and beyond the outer and inner faces of the door —A— and across the chamber —a—, the outer end and portion which extends across the chamber —a— being angular or square in cross section for a purpose presently described, while the other shaft section —5— is preferably tubular and journaled upon the inner end of the shaft section —4— and is extended through the inner side of the door partially across the chamber —a— and some distance inwardly beyond the door for receiving and supporting a handle —6— which is secured to the inner end of the tubular shaft section —5— by a set screw —7— or equivalent fastening means.

The inner end of the shaft section 4 is cylindrical to permit it to turn freely in the tubular section —5— and is provided with an annular groove —8— for receiving a key or pin —9— by which the two shaft sections are normally held against relative endwise movement while permitting either to turn freely upon the other.

A suitable wear plate —10— is secured to the inner face of the door —A— around the tubular section —5— to be engaged by the hub of the handle —6— for additionally holding the shaft section —5— against undue endwise movement in one direction.

A suitable handle —11— is secured by a screw —12— or equivalent fastening means to the outer end of the shaft section —4— in spaced relation to the outer face of the plate

—1—to permit the turning of the shaft section —4— independently of the shaft section —5— for a purpose presently described.

5 The inwardly offset portion of the plate —1— across the inner edge of the door —A— is provided with a guide opening —13— in which is movable one end —14— of a bolt —15—, the end —14— of the bolt being normally extended through a registering opening in the keeper plate —3— and into the chamber —a— to hold the door in its locked position and has its inner face beveled for sliding engagement with the keeper to automatically force the bolt inwardly beyond the keeper when closing the door.

10 The portion of the bolt —15— within the chamber —a— is widened and bifurcated to form opposite arms —16— having inwardly turned projections —17— at opposite sides of and equal distances from the axis of the shaft sections —4— and —5—.

15 The bolt —15— is yieldingly held in its locking position by means of a flat spring —18— having its intermediate portion engaged with the periphery of the tubular shaft section —5— within the chamber —a— and its opposite ends bearing against the inner faces of the upturned lugs or shoulders —17— and tensioned to force the bolt to its locking position but yieldable to permit the bolt to be drawn inwardly to its unlocked position in a manner hereinafter described.

20 The tubular shaft section —5— is provided with oppositely projecting similar arms —19— within the chamber —a— and adjacent the inner face of the bolt —15— for engaging the lugs —17— opposite the ends of the spring —18— so that the turning of the handle —6— and tubular shaft —5— in either direction will cause one or the other of the arms —19— to engage the corresponding lug —17— and thereby withdraw the bolt —15— from its locking position independently of the shaft section —4— and its operating handle —11—, see Figure 3.

25 A supplemental bolt operating plate —20— is reciprocally movable lengthwise of and adjacent the outer face of the bolt —15—, Figure 2, and is provided at one end with oppositely projecting lugs or shoulders —21— and —22—, one of which projects into an elongated slot —23— in the bolt —15— some distance from the axis of the shaft section —4— and is normally engaged with the inner end wall of the slot when the bolt is in its locking position, the opposite lug —22— projecting toward the plate —1—.

30 The other end of the supplemental plate —20— is bifurcated to form opposite arms —24— at opposite sides of the axis of the shaft sections —4— and —5— and between the arms —16— of the bolt —15— as shown in Figure 4, said arms —24— being provided with upturned lugs —25— normally in sub-

stantially the same transverse plane as the lugs —17— of the bolt —15— when the latter is in its locking position.

35 A hub —26— having an angular opening therethrough is mounted upon the shaft section —4— within the chamber —a— and directly against the adjacent end of the tubular shaft section —5— and is provided with oppositely projecting arms —27— Fig. 4, for engaging the adjacent lugs —25— of the plate —20— whereby the turning of the shaft section —4— by its handle —11— in either direction will draw the plate —20— inwardly thereby engaging its lug —21— with the adjacent end wall of the slot —23— for simultaneously withdrawing the bolt —15— from its locking position independently of the tubular shaft section —5— and its operating handle —6—.

40 The length of the slot —23— beyond the lug —21— is sufficient to allow the bolt —15— to be withdrawn from its locking position by the turning movement of the shaft section —5— in either direction.

45 It is now evident that the bolt —15— is automatically forced to its locking position by the spring —18— and that it may be withdrawn from said locking position against the action of the spring by the turning movement of the tubular shaft section —5— in either direction through the medium of the handle —6— which causes one or the other of the arms —19— to engage the corresponding lug —17— of the bolt —15— to withdraw the latter inwardly independently of any turning movement of the shaft section —4— and its handle —11—.

50 The bolt —15— may be withdrawn from its locking position by the turning of the handle —6— at the inside of the door in either direction but suitable means is provided for preventing the turning movement of the outer handle —11— and its corresponding shaft section —4— until certain controlling elements hereinafter described have been previously adjusted to certain positions.

55 For this latter purpose, a circular disk —28— is brazed or otherwise secured to the inner face of the plate —1— and is provided with a series of inwardly projecting shoulders or lugs —29— arranged in uniformly spaced relation circumferentially about the axis of the shaft sections —4— and —5—, to be engaged by springs —29— which are secured to the hub of a disk —30— (one of the lock-controlling disks) in a manner and for a purpose hereinafter described.

60 The disk —28— and plate —1— are provided with registering openings co-axial with the shaft sections for receiving a tubular sleeve —31— which extends beyond the inner face of the disk —28— and also beyond the outer face of the plate —1— and is provided on its inner end with the bolt-controlling disk —30—.

—30— rigid therewith for angular adjustment with said sleeve.

A similar, but somewhat longer sleeve —33— is mounted for angular adjustment 5 within the sleeve —31— to extend beyond the opposite ends thereof around the shaft section —4— and is provided on its inner end with a bolt-controlling disk —34— rigid therewith and adjacent the inner end of the 10 disk —30—.

The outer end of the sleeve —31— is provided with an operating handle —35— by which it, together with the disk —30—, may be adjusted rotarily relatively to the shaft 15 section —4— and inner sleeve —33—.

This handle —35— preferably consists of a peripherally graduated section —36— and nut section —37—, both of which are mounted upon the outer end of the sleeve —31—, 20 the section —36— being provided with a series of internal notches —38— arranged in uniformly spaced relation circumferentially for receiving a projection or key —39— on the periphery of the sleeve —31— while the 25 section —37— is threaded internally and engaged with the outer threaded end of the sleeve —31— so that by removing the nut section —37— the other section —36— may be displaced axially from the key —39— and 30 then turned any part of a revolution to register any one of the other notches —38— with the lug 39 as may be required for changing the combination of the controlling disks.

In like manner the outer end of the sleeve 35 —33— is provided with an operating handle —40— surrounding the outer end of the sleeve adjacent the outer face of the handle —35— and consisting of an inner section —41— and an outer section —42—, the inner 40 section —41— like the section —36— being provided with a series of internal notches arranged in uniformly spaced relation circumferentially for receiving a lug or key on the periphery of the sleeve —33— while the 45 section —42— is threaded internally and engaged with the outer threaded end of the sleeve —33—.

The nut section —42— may be removed to 50 permit the displacement of the section —41— for angular adjustment thereof to register any one of its notches with the corresponding key for additionally changing the combination of the controlling disks —30— and —34—. These disks —30— and —34— are 55 disposed in the plane of the lug —22— and are provided with radial slots —44— extending inwardly from the periphery thereof and adapted, when properly adjusted, to permit the unlocking of the bolt —15— by the handle —11— and its shaft section —4— to register with the lug —22— but at other times to be out of registration with each other and also out of registration with said lug to prevent the withdrawal of the bolt-controlling plate —20— and thereby prevent the

angular adjustment of the handle —11— and its shaft section —4—.

The sleeve —33— carrying the disk —34— is rotatable relatively to the angular shaft —4— by means of its operating handle 70 —40— while the sleeve —31— carrying the disk —30— is rotatable relatively to the disk —34— and shaft —4— by means of its operating member —35— thus permitting the radial slots —44— in the disks —30— and 75 —34— to be moved into and out of registration with each other and also into and out of registration with the lug —22— on the sliding plate —20—.

The springs —29— are mounted upon the 80 disk —30— to rotate therewith and to successively engage the lugs —29— on the disk —28— when the disk —30— is rotated continuously in either direction in which case the springs will be placed under more or less tension when riding across the inner faces 85 of the lugs —29—, said springs being shown in Figure 5 as under partial tension due to the rotation of the disk —30— in the direction indicated by arrow —x—, Figure 5.

The object of the stop lugs —29— and their 90 cooperating springs —29— is to enable the operator to sense the adjustment of the disk —30— to different positions and also to normally hold the disk in such position of rest that its slot —44— will be out of alignment 95 with the lug —22— and thereby to prevent the operation of the slide —20— by the rotary adjustment of the handle —11— and its shaft —4— through the medium of the arms —27—.

The handle sections —36— and —41— of the handles —35— and —40—, respectively, 100 are cylindrical and provided with peripheral graduations numbered in sequence circumferentially from a given point as shown in Figure 6 while the other sections —37— and —42— of the same handles are also cylindrical and knurled peripherally to facilitate the angular adjustment of the sleeves —31— and —33— and their respective lock-controlling disks —30— and —34— as may be required 105 to bring the slots —44— into and out of registration with the lug —22—.

The graduations on the peripheries of the 110 disks —36— and —41— are adapted to be brought into registration with a fixed index or starting point —45— on the plate —1— Fig. 1, so that when any two previously selected graduations of the combination are 115 registered with the index —45— the slots —44— of the disks —30— and —34— will be brought into registration with the lug —22— thus permitting the slide —20— to be 120 operated by the rotation of the shaft —4— in either direction for withdrawing the bolt —15— from its locking position.

If the disks —30— and —34— have been 125 adjusted to permit the unlocking of the bolt —15— and both the bolt —15— and plate 130

—20— have returned to their normal locking positions, said disks —30— and —34— will be rotated by their respective handles —35— and —40— to move the slots —44— 5 out of registration with the lug —22— thereby bringing the solid portions of the disk in opposed relation to said lug to prevent the withdrawal of the slide —20— and bolt —15— from their locking positions and incidentally preventing the turning movement 10 of the shaft —4— and handle —11—.

These last-named operations are, of course, to prevent the opening of the door by unauthorized persons unfamiliar with the combination of numbers on the disks —36— and —41— required to be registered with each other and with the index —45— on the plate —1—.

For example, assuming that the graduated disks —36— and —41— have been set so that their graduations —40— and —90— are brought into diametrical alignment with the slots —44— of the disks —30— and —34— respectively, then it will be necessary to register both of these graduations —40— and —90— with the fixed index —45— in order to bring the slots —44— into registration with the lug —22— to allow the opening of the bolt —15— by the turning of the shaft —4— through the medium of its handle —11—.

Under this setting of the graduation members —36— and —41— if they are not registered with each other or either or both of them are not registered with the index —45— the slots —44— will not be registered with the lug —22— and, therefore, the plate —20— cannot be operated to unlock the bolt —15— by the turning of the handle —11—.

Whenever it becomes necessary or desirable to change the combinations on the disks —36— and —41— it may be readily done by temporarily removing the handle —11— and knurled nuts of the handles —35— and —40— and then readjusting the graduation members —36— and —41— to produce any other combinations of graduations within the range of the numbers of said disks.

What I claim is:—

50. 1. The combination with a door having a lock-receiving recess and a casing having a keeper for the lock, of relatively rotatable coaxial shaft sections extending through registering openings in the door and across the recess therein and telescoping with each other within the recess, said shaft sections having their outer ends provided with handles for rotating the same, a bolt mounted on the door and movable into and out of engagement with the keeper and normally spring-pressed into engagement with said keeper, means actuated by the turning movement of one of said shaft sections for withdrawing the bolt from its locking position, a bolt-operating plate ad-

5 jacent the bolt within said recess, means actuated by the turning movement of the other shaft section for actuating the bolt-operating plate to withdraw the bolt from its locking position independently of the operation of the first-named shaft section, a disk within 70 said recess and adjacent the bolt-operating plate and adjustable rotatably about the axis of the second-named shaft section relatively thereto, a lug on the bolt-operating plate extending across the periphery of the disk, said 75 disk having a slot extending inwardly from the periphery thereof and movable therewith into and out of registration with said lug for controlling the operation of the bolt-operating plate and preventing the turning 80 movement of the second-named shaft section when the slot is out of registration with the lug.

2. In a door lock of the character described, the combination with a door, relatively rotatable coaxial shaft sections extending through registering openings in the inner and outer sides of the door respectively in telescopic relation, a handle on the inner end of the inner shaft section for turning the same, an additional handle on the outer end of the outer shaft section for turning the same, a bolt slideable transversely of the axis of said shaft sections and extending beyond opposite sides thereof, arms secured to and projecting laterally from opposite sides of the inner shaft section for engaging and withdrawing the bolt from its locking position as the inner shaft section is turned about its axis, a bolt-operating plate movable lengthwise of the bolt and provided with means for engaging and withdrawing the bolt from its locking position when moved in one direction, means actuated by the turning movement of the outer shaft section for actuating the bolt-operating plate, a sleeve surrounding the outer shaft section coaxial therewith and rotatable relatively thereto, an additional sleeve surrounding the first-named sleeve coaxial therewith and rotatable relatively thereto, a disk secured to the first-named sleeve to rotate therewith, an additional disk secured to the second-named sleeve to rotate therewith, separate devices on the outer ends of the sleeves for rotating the same and a lug on the bolt-operating member extending across the peripheries of both of the disks, said disks having slots extending inwardly from the peripheries thereof and movable into and out of registration with said lug to permit the lugs to enter the slots for withdrawing the bolt from its locking position when the bolt-operating plate is operated by the turning movement of the outer shaft section.

In witness whereof I have hereunto set my hand this 16th day of June 1927.

JAY M. WESTCOTT.
